UNITED STATES PATENT OFFICE.

BENJAMIN U. CUENY, OF SPRINGFIELD, MASSACHUSETTS, ASSIGNOR TO TABER-PRANG ART CO., OF SPRINGFIELD, MASSACHUSETTS, A CORPORATION OF MASSACHUSETTS.

ALBUM OR HOLDER FOR PHOTOGRAPHS.

1,415,429.

Specification of Letters Patent.

Patented May 9, 1922.

Application filed June 10, 1921. Serial No. 476,500.

To all whom it may concern:

Be it known that I, BENJAMIN U. CUENY, citizen of the United States, residing at Springfield, in the county of Hampden and 5 State of Massachusetts, have invented new and useful Improvements in Albums or Holders for Photographs, of which the following is a specification.

The present invention relates to albums or 10 display holders for photographs or the like and has for its object to provide certain new and useful improvements in devices of this character.

The invention consists in the novel and 15 improved construction and combination of parts hereinafter described and particularly pointed out in the appended claim, reference being had to the accompanying drawings forming a part of this specification.

20 In the drawings—

Fig. 1 is a perspective view of an album or holder embodying the present invention in what is now considered to be its preferred form, the album being shown with 25 its covers closed and standing in upright position.

Fig. 2 is a fragmentary cross-sectional view of the album in partially open condition.

30 As shown in the drawings, the album or display holder comprises a plurality of leaves 3, a binder 4 for the leaves, and a pair of covers 5 which are hinged together as indicated at 6, and to which the binder 35 4 is securely fastened.

The leaves 3 are adapted to receive the photographs or other display matter. To this end the leaves may be slotted or otherwise constructed to detachably receive the 40 photographs or, if desired, plain leaves may be provided and the photographs pasted thereon.

The binder 4 is of the expandable type and 45 consists of a plaited sheet of cloth or similar material. The leaves 3 are glued or otherwise suitably secured to the binder 4, one leaf having its inner edge portion secured to one of the folds of each plait of the binder, as shown in Fig. 2.

50 The covers 5 may be composed of any suitable stiff material. As shown, each cover 5 consists of a rectangular wooden frame 7

having its inner edge faces rabbeted to receive the marginal portions of a relatively thin panel 8 constituting the body portion of 55 the cover. The size of the frames 7 and the relative arrangement of the panels and frames is such that recesses 9 are formed in the covers adapted to receive the leaves 3. The hinges 6 are secured to the frame 7 in 60 such a manner as to permit the closing of the covers 5 until the opposed sides of the frames 7 are brought into engagement with each other as shown in Fig. 1. The plaited binder 4 is arranged adjacent the hinged 65 edges of the covers 5 and the opposite ends of the binder are firmly secured to the inclosing sides of the panels 8. The recesses 9 are of sufficient size and depth to readily receive the leaves 3 and when the covers are 70 closed, the leaves together with the photographs mounted thereon, lie entirely within said recesses, and the covers are permitted to close tightly together so that the edges of the leaves will be entirely surrounded by 75 the frames 7. In this way, when the covers are closed the album leaves and the photographs are protected from dust and injury. The construction of the binding 4 and the manner in which it is secured to the covers 80 5 permit the latter to be readily opened as wide as desired without in any way weakening the binding. Suitable inter-engaging clasp members 10 may be provided on the frames 7 to hold the covers closed. 85

The covers 5 may embody various ornamental designs, and either or both of the covers may bear appropriate pictures, legends, or display matter more or less suggestive or descriptive of the photographs or other material mounted upon the leaves of 90 the album.

The particular construction and arrangement of the covers above described is such that when the album is closed it bears little 95 resemblance to an album of the ordinary type inasmuch as the leaves thereof are not visible but are entirely enclosed and protected within a chamber formed by the conjunction of the recessed portions 9 of the 100 covers. When closed, however, the illustrated album closely resembles a picture frame of the sort commonly used for small photographs.

In order that the album may be supported in upright position, after the manner of a framed photograph, each cover 5 is provided with a pedestal 11 preferably of greater width than the frame. By means of the pedestals 11 the album may be conveniently supported in upright position whether the covers are open or closed.

It will be appreciated that the present invention is capable of embodiment in albums or holders of a wide variety of ornamental designs whereby the albums may be made unusually attractive in appearance and, if desired, more or less suggestive of the class of matter contained therein. It should also be understood that while it is preferred to employ the specific construction and arrangement of parts shown and described, such construction is not essential except so far as defined in the claim and may be variously changed or modified without departing from the spirit and scope of the invention.

Having thus described the invention, what

is claimed and desired to be secured by Letters Patent, is:—

A display album having, in combination, a plurality of leaves, a pair of covers comprising rectangular frames hinged together and having panels fitted therein to provide recesses at both the inner and outer sides of the covers, the construction being such that the inner recesses will receive said leaves and the inner faces of the frames will abut each other when the album is closed so that the edges of the leaves will then be entirely enclosed within said frames, an expandable binder for securing the leaves to the covers, a thickened pedestal centrally located beneath the lower side of each frame for firmly supporting the album in upright position whether the same be opened or closed, and a clasp for positively securing the covers in closed position.

In testimony whereof I have affixed my signature.

BENJAMIN U. CUENY.
